UNITED STATES PATENT OFFICE.

JULIUS KRUTTSCHNITT, OF NEW CANAAN, CONNECTICUT.

REINFORCED-CONCRETE RAILROAD TIE.

Application filed September 29, 1920, Serial No. 413,610. Renewed May 4, 1923.

To all whom it may concern:

Be it known that I, JULIUS KRUTTSCHNITT, a citizen of the United States, residing at New Canaan, county of Fairfield, State of Connecticut, have invented new and useful Improvements in Reenforced-Concrete Railroad Ties, of which the following is a specification, reference being had to the accompanying drawings, in which—

10 Fig. 1 is an elevation of my improved tie partly in section; Fig. 2 is a partial plan thereof, also partly in section; Fig. 3 is a perspective partially broken away to show the arrangement of the reinforcing bars; 15 Figs. 4 and 5 are sections respectively on lines IV—IV and V—V of Fig. 2; and Figs. 6 and 7 are sections respectively on lines VI—VI and VII—VII of Fig. 1.

My invention relates to railroad ties and 20 comprises a reenforced concrete tie having therein cushioning blocks to which the tie plates and rails are attached, and the securing means for which also act to retain the blocks in position in the tie. My improved 25 tie is so designed that the reinforcing bars are arranged to give it the necessary strength, to prevent the cracking of the concrete when the blocks are driven in and to resist unbalanced stresses when the load on 30 the tie is not equally distributed. My invention also consists in the construction and arrangement of parts which I shall herein- 35 after describe and claim.

Referring to the drawings, the tie A, 35 which is made of reenforced concrete, is substantially rectangular in cross section and has laterally extending flanges 2 which give it a broad bearing surface and afford a large area to prevent shifting, and recesses 40 or panels 3 in the sides thereof into which the ballast is tamped, and which anchor the tie particularly against endwise movement on curves. The rails B are connected to the ties A through the wedge-shaped rail blocks 45 4, which are preferably made of creosoted wood. The blocks of each pair meet in the long axis of the tie and are seated in a pocket or recess 5 of double wedge shape in the top of the tie. Each recess 5 also has 50 undercut sides 6, so as to hold the wooden blocks 4 from vertical movement relative to the tie, so that side walls 6 of each recess are tapered both vertically and horizontally. The rails B are secured to the ties by means 55 of tie plates 7, spiked or otherwise fastened to the wooden blocks, and the wooden blocks

4 are held from outward movement along the axis of the rail by spikes 8 driven through apertures in the tie plates 7. It will thus be seen that each tie plate 7 holds in position by 60 its spikes the pair of blocks upon which it is seated.

The tie is reenforced by the bars 10, 11, 12, 13, 14 and 15, all of which, with the exception of the bars 15, extend for substantially 65 the length of the tie. Each bar lies in a separate vertical plane, except where the bars 11 and 13 pass each other in the region of the recess 5, and the ends of the bars 11 and 13, and 10 and 12, are turned to overlap 70 each other in the ends of the ties, and except that the ends of the bars 14 are turned into a horizontal plane. The ends of the bars 10, 11, 12 and 13 are turned upwardly or downwardly substantially into a vertical plane. 75 The bars 11 are bent in the form of a truss support immediately under the recesses 5, while the bars 10 and 13 are bent to reinforce the corners of the rail seats to prevent splitting of the concrete at these points, and 80 also to aid in taking care of diagonal tensile stresses. The bars 15, which extend under the recesses 5 and a short distance either side thereof, serve to resist the tensile stresses developed in the bottom of the tie 85 immediately under the recesses 5.

The longitudinal bars 10, 11, 12, 13, 14 and 15 are bound together by tie rods 16, which not only serve to locate and anchor the bars in the concrete but also to prevent 90 shearing stresses.

Ties constructed in accordance with my invention have the following advantages: Fewer ties are required than where wooden ties are used, owing to the greater and more 95 unyielding bearing area provided, which also results in employing a smaller number of track fasteners; the wooden blocks 4, which are driven and held in the accurately located recesses, make the gauge easy to 100 maintain; the wooden blocks are of a size sufficient to afford ample insulation where electrical insulation is required; the blocks act to cushion the rails and thus lessen the noise and vibration and add to the comfort of travel; and bolts or other fastenings between tie and wood blocks are unnecessary and replacement of the blocks may therefore 105 be readily made.

In the section of the tie between the rails, 110 the bars 10, 11, 12 and 13 are located as near the surface of the tie as possible in

order to give the maximum lever arm, thus resisting tension in the upper portion of the tie and assisting the concrete to resist compression in the bottom portion under one 5 load condition, or under a reversal of load conditions to take care of compression in the top and tension in the bottom portion of the tie.

In the section beneath the rails the bars 10, 11, 12 and 13 are spaced for a maximum leverage, and the bars 15 serve to increase the available steel area designed to resist the tensile stresses developed in the bottom of the tie.

15 The terms and expressions which I have employed are used as terms of description and not of limitation, and I have no intention, in the use of such terms and expressions, of excluding any equivalents of the 20 features shown and described, or portions thereof, but recognize that various modifications are possible within the scope of the invention claimed.

What I claim is:

25 1. A reenforced concrete railroad tie having in its upper surface a plurality of recesses, each recess being adapted to receive a pair of blocks, means on the tie for holding each of the blocks from movement in one 30 direction transverse to the axis of the tie and rail-fastening means secured to the blocks adapted to prevent movement of each said block in the opposite direction.

2. A reenforced concrete railroad tie having in its upper surface a plurality of recesses flaring outwardly toward the sides thereof, a pair of blocks, each of wedge shape, seating in each of said recesses, and rail fastening means securing the said blocks 40 from movement outward of the axis of the tie.

3. A reenforced concrete railroad tie having in its upper surface a plurality of recesses for rail supports, each of the said recesses being of least width on the longitudinal axis of the tie and inclining horizontally and vertically therefrom, a pair of similarly shaped blocks seating in each such recess and conforming to the shape of the recess, 45 and means associated with the rail for holding each of said blocks from movement in one direction transverse to the tie.

4. A reenforced concrete railroad tie hav-

ing in its upper surface two recesses for rail supports, a pair of blocks fitting in each recess, each recess being inclined to the horizontal to limit the inward movement of each block and inclined to the vertical to prevent the upward movement of each block and rail fastening means secured to each pair of blocks.

5. A reenforced concrete railroad tie having in its upper surface two recesses, rail supporting blocks seating in said recess, a reinforcing bar having its ends lying in the lower plane of the tie and having an intermediate portion bent upwardly into truss form beneath and in the region of a recess, another bar arranged substantially in the plane of the ends of the first mentioned bar, 70 spanning the space under the said intermediate portion in the region of said recess to resist tensile stresses in the bottom of the tie, and reinforcing members securing said bars together. 75

6. A reenforced concrete railroad tie having in its upper surface two recesses, rail supporting blocks seating in said recesses, reinforcing bars arranged respectively in planes near the top and bottom of the tie, certain of said bars in each of such planes having an intermediate portion thereof bent to occupy a different plane in the region of the said recesses to provide reinforcement against tensile and compressive stresses about said recesses, and transversely arranged tie rods securing the bars together. 80

7. A reenforced concrete railroad tie rectangular in cross section and with a pedestal base having rail supporting recesses in the upper surface thereof extending from side to side of the tie, a pair of blocks seated in each of said recesses adapted to be brought substantially into contact in the longitudinal axis of the tie, rail fastening means securing the rail to the blocks and adapted also to hold the blocks from movement longitudinally of the rail, and reinforcing bars extending longitudinally of the tie, certain of the bars being angled in the region of the 90 recesses to prevent cracking of the concrete thereabout and to resist compressive and tensile stresses, and transversely arranged tie rods securing the bars together. 100

JULIUS KRUTTSCHNITT.
